UNITED STATES PATENT OFFICE.

FRANK W. ROLLER, OF NEW YORK, N. Y.

DESIGN FOR A CASE FOR ELECTRICAL MEASURING INSTRUMENTS.

SPECIFICATION forming part of Design No. 34,502, dated May 14, 1901.

Application filed March 30, 1901. Serial No. 53,733. Term of patent 7 years.

To all whom it may concern:

Be it known that I, FRANK W. ROLLER, a citizen of the United States, residing at New York, in the county of New York and State of New York, have invented and produced a certain new and original Design for a Case for Electrical Measuring Instruments, of which the following is a full, clear, and exact specification.

10 My design relates to cases for electrical measuring instruments, and its object is to provide an attractive form of case in which the mechanisms of instruments may be conveniently and compactly arranged.

15 The design will be more particularly described with reference to the accompanying drawing, in which the figure represents a perspective view of the case.

The leading features of the design are the 20 substantially rhombic or rhomboidal contour

of the cap 1 and the substantially perpendicular arrangement of the sides 5.

In the drawing, 2 and 3 represent openings in the upper and lower portions of the cap 1, 25 4 the calibrated scales of the measuring instruments ordinarily contained in the case, and 6 the base upon which the case ordinarily rests.

Having thus described and illustrated my invention, I claim—

30 The design for a case for electrical measuring instruments herein described and illustrated.

In testimony whereof I affix my signature in presence of two witnesses.

FRANK W. ROLLER.

Witnesses:

C. V. EDWARDS,
HENRY BEST.
